(57) **CLAIM**

The ornamental design for a sporting implement, as shown and described.

DESCRIPTION

FIG. 1 is a top, left, rear perspective view of a sporting implement showing our new design;

FIG. 2 is a rear view thereof;

FIG. 3 is a left side view thereof; and,

FIG. 4 is a cross-sectional view at 4-4 in FIG. 2 thereof. The uneven-length broken lines represent unclaimed boundaries of the claimed design. The even-length broken lines showing the remainder of the sporting implement represent unclaimed subject matter and form no part of the claimed design.
